(57) **CLAIM**

(21) Appl. No.: **29/129,850**

The ornamental design for a box for information transmission apparatus, as shown and described.

(22) Filed: **Sep. 22, 2000**

DESCRIPTION

(30) **Foreign Application Priority Data**

Jul. 4, 2000 (SE) 127157

FIG. 1 is a perspective view of the box for information transmission apparatus;

(51) LOC (7) Cl. **14-02**

FIG. 2 is a front view thereof;

(52) U.S. Cl. **D14/336**

FIG. 3 is a rear view thereof;

(58) **Field of Search** D14/336, 337,

FIG. 4 is a left side view thereof;

D14/341, 345, 374, 343, 126-129, 347;

FIG. 5 is a right side view thereof;

D18/1, 2, 7; D19/26, 52, 59, 60; 345/104,

FIG. 6 is a top view thereof; and,

156, 173, 168; 349/12; 178/18.03, 18.08

FIG. 7 is a bottom view thereof.
